SASH-HOLDING DEVICE

Robert H. Breitenbach and Leon E. Willett, Detroit, Mich., assignors to Chamberlin Metal Weather Strip Company, Detroit, Mich., a corporation of Michigan

Application May 13, 1941, Serial No. 393,208

13 Claims. (Cl. 292—74)

This invention relates to sash-holding structures, and particularly to weightless sash-holding devices.

One object of this invention is to provide a sash-holding device which applies a more powerful force against downward motion of the sash than upward motion, so that the weight of the window sash will be firmly sustained when the window is open, yet will require only a slight lifting force to raise the window.

Another object is to provide a sash-holding device wherein a less powerful force is required to open the window than to close it.

Another object is to provide a sash-holding device wherein a frictional member is yieldingly urged against the weatherstrip or a portion of the window frame in such a manner that the downward force applied to close the window is less than the upward force required to raise it or hold it in a fixed position against the downward force of its weight.

Another object is to provide a sash-holding device as set forth in the foregoing objects wherein mechanism is provided for finely adjusting the position of the friction member relatively to the window portion or weatherstrip engaged thereby.

Another object is to provide a sash-holding device as set forth in the foregoing objects wherein mechanism is provided for increasing or decreasing the pressure exerted against the friction member which engages the window frame portion or weatherstrip.

Another object is to provide a sash-holding device as set forth in the foregoing objects wherein an adjustment is accessible from the top or bottom of the window sash for varying the force by which the window is frictionally held open.

Another object is to provide improved means for securing a sash-holding device to a window sash as set forth in the preceding objects.

In the drawings:

Figure 1 is a side elevation, partly in section, of a preferred embodiment of a sash-holding device according to the present invention.

Figure 2 is a top plan view of the sash-holding device of Figure 1 taken in section along the line 2—2 therein.

Figure 3 is a vertical section taken along the line 3—3 in Figure 1.

Figure 4 is a cross section taken along the line 4—4 in Figure 1.

Figure 5 is a perspective view of the working unit portion of the sash-holding device of Figure 1.

Figure 6 is a perspective view of the container for the working unit shown in Figure 5.

Figure 7 is a side elevation, partly broken away, of a window sash and frame assembly with the sash-holding device of Figure 1 installed.

Figure 8 is a top plan view of a modification of the sash-holding device of Figures 1 and 2, showing the device installed to exert pressure at right angles to the plane of the window pane.

5 Figure 9 is a top plan view of another modification similar to Figures 2 and 8 but adapted to exert pressure against the side of the window frame in the plane of the window pane.

Figure 10 is a side elevation similar to Figure 3 10 but showing a further modification thereof wherein a bent metal frame is provided for the adjusting pins instead of the solid bar of Figure 3.

Figure 11 is a view similar to Figure 1 but 15 showing a further modification wherein an adjustment is provided for directly varying the spring pressure exerted upon the sash holding friction member.

Figure 12 is a top plan view of Figure 11 taken 20 partly in section along the line 12—12 therein.

Figure 13 is a vertical section taken along the line 13—13 in Figure 11.

Figure 21 is a perspective view of the modified 45 friction-applying member used in the modification of Figure 18.

Figure 22 is a perspective view of the adjusting member used with the friction-applying member of Figure 21.

Figure 23 is a perspective view of the modified 50 container used with the modified friction-applying member and adjusting member of Figures 21 and 22 respectively.

General arrangement

In general, the sash-holding device of this invention 55 consists of a friction-applying unit installed in a recess in one of the vertical members of the window sash. This friction-applying unit consists of a friction member which is urged by a spring into engagement with the weatherstrip or a portion of the window frame. The

friction member is mounted on a channel member having diagonal slots in its opposite sides. These diagonal slots are engaged by pins in a longitudinally adjustable carrier having a screw for moving this carrier to and fro. The motion of this carrier causes the pins to engage the diagonal slots at different points therein and hence causes the channel member and the friction member carried by it to occupy different positions laterally. A coil spring urges the channel member longitudinally, this longitudinal movement being converted into a lateral movement of the friction member by the engagement of the pins with the diagonal slots.

In a modification of the invention (Figure 8), the friction member engages a portion of the window frame in a direction perpendicular to the direction of the window pane instead of the weatherstrip, as in the principal form (Figure 2). In a second modification (Figure 9), the friction-applying unit is mounted at right angles to its position in the previous modification (Figure 8) so that the friction member engages the side of the window frame in a direction parallel to the plane of the window pane.

In a third modification (Figure 10), the pins which engage the diagonal slots in the channel member are mounted in a carrier composed of a bent metal strip instead of in a solid bar as in the principal form (Figures 3 and 5). In a fourth modification (Figure 11), the pins are fixed, the adjustment being applied directly to the spring in order to increase or decrease the thrust applied to the friction member.

In a fifth modification (Figures 18 to 23), the adjustable carrier is provided with diagonal slots for the pin on the friction-applying unit.

Sash-holding device with adjustable guide pins

Referring to the drawings in detail, Figures 1 to 7 inclusive show the preferred form of the invention as applied to a lower window sash 10 and an upper window sash 11 movable up and down within a window frame 12 (Figure 7). Each window sash (10 or 11) has horizontal members 13 and vertical members 14 (Figure 7) forming a frame for the window pane 15 in the usual way. The vertical sash member 14 is provided with an elongated vertical groove 16 in which is mounted the sash-holding device generally designated 17. The window frame 12 is provided with the usual groove 18 having side walls 19 and front and rear walls 20 and 21 respectively. A metal weatherstrip member 22 is inserted in the groove 18 and is bent to provide a tongue or rib 23 entering the groove 16. The weatherstrip 22 is likewise provided with a bent portion 24 arranged between the outer face 25 of the vertical sash member 14 and the front wall 20 of the window frame groove 18.

The sash-holding device 17 consists of a container generally designated 26 (Figure 6), preferably of bent sheet metal and serving to receive the friction-applying unit generally designated 27 (Figure 5). The container 26 consists of elongated side walls 28 and 29 bent at right angles to each other. The side wall 28 terminates at its upper end in a tab 30 perpendicular thereto, and also at its upper and lower ends carries corner portions 31 and 32 consisting of tabs 33, 34, 35 and 36 bent respectively to form such corners (Figure 6). The side wall 29 is provided at its upper and lower ends with tabs 37 and 38 adjacent and aligned with the tabs 34 and 36 on the corner portions 31 and 32.

The friction-applying unit 27 which is inserted in the space defined by the side walls 28 and 29 and the tabs 33 to 38 inclusive consists of an elongated channel member 40 having a central portion 41 and parallel side portions 42. Secured as at 43 to the central portion 41 of the channel member 40 is a friction member 44 of any suitable friction-applying material, such as fiber or the like. The side portions 42 of the channel member 43 are provided with oblique upper and lower pairs of slots 45 and 46 disposed at an angle to the central portion 41. Received within and engaging these oblique or diagonal slots 45 and 46 are pins 47 and 48 mounted in the arms 49 and 50 respectively of a U-shaped elongated carrier generally designated 51 and having an elongated portion 52 joining the two arms 49 and 50. The upper arm 49 is provided with a threaded longitudinal hole 53 which receives the threaded portion 54 of a screw 55 (Figures 1 and 3). The upper end of the screw 55 is provided with an annular groove 56 engageable with the opposite tabs 34 and 37 and entering the space between them so as to anchor the screw 55 in a fixed position longitudinally while permitting its rotation. Near its lower end, the channel member 40 is notched as at 57 to provide an anchorage for a partition member 58 (Figures 3 and 5), the latter being secured as at 59a to the central portion 41 of the channel member 40. Engaging the partition member 58 in the upper end of a coil spring 59, the lower end of which engages the tabs 36 and 38 as an abutment. The coil spring 59 thus urges the channel member 40 and the friction member 44 in a diagonally upward direction, guided by the adjustable guide pins 47 and 48.

The sash-holding device 17 is assembled by placing the coil spring 59 in position beneath the partition 58 and at the same time sliding the friction-applying unit 27 into the container 26 (Figures 5 and 6) with the annular groove 56 of the screw 55 entering the space between the tabs 34 and 37. The sash-holding device 17 may then be installed in the groove or recess 16 in the vertical sash members 14 in any suitable way. This may be done by inserting screws 60 and 61 through the screw holes 62 and 63 in the upper and lower ends of the container 26 (Figure 6), thereby firmly securing the device to the window sash. The position of the friction member 44 may then be accurately adjusted by rotating the screw 55 by means of a screw driver, thereby causing the guide pins 47 and 48 to move up or down in the slots 45 and 46.

In the operation of the sash-holding device of Figures 1 to 7 inclusive, the screw 55 is adjusted in the above-described manner until the friction member 44 engages the weatherstrip portion 23 with sufficient force to hold the window in an open position, yet permit it to be closed by the application of a sufficient force to the top member 13 of the window sash. As the window is raised to open it, the channel member 40 and friction member 44 attached thereto yields slightly, compressing the spring 59 but permitting the parts to slide relatively to each other. When the window is closed, however, the guide pins 47 and 48 engage the diagonal grooves 45 and 46 and tend to push the friction member 44 against the weatherstrip portion 23 with a firm and increased grip, thereby applying more friction and requiring a greater force to close the window than to open it. This action not only serves to counteract the weight of the window when it is open,

but also assists the operator in opening and closing the window. In closing the window, the operator can use his own weight to assist him, hence a relatively great resistance can be set up to prevent accidental closing of the window. In opening the window, however, the operator has only the unassisted power of his arms, hence the resistance to be overcome in lifting the window is decreased by the invention so that it is but slightly more than the weight of the window sash and its associated parts.

Modifications of container and guide pin carrier

The modification shown in Figure 8 employs the same friction-applying unit 27 as in Figures 1 to 7 inclusive so that the friction member 44 directly engages the front wall 20 of the groove 18 in the window frame 12 rather than the weatherstrip portion 23. This is accomplished by forming the recess 16a for the device as a notch extending entirely out to the edge of the sash rather than as a mere groove 16 with side walls (Figure 2). Thus the installation of Figure 8 may be made in windows which are not equipped with weatherstrips.

The modification shown in Figure 9 is similar to that shown in Figure 8 except that the friction member 44 engages the side wall 19 of the groove 18 in the window frame 12 rather than the front wall 20. In order to accomplish this, the tab 30a of the container 26 in Figure 9 is shortened so as to fit the portion 64 of the sash member 14 instead of the main portion of the latter as in Figure 2. In other words, the tab 30a is swung around 90 degrees from the position of the tab 30 in Figure 2.

The modification shown in Figure 10 employs a bent metal carrier 65 having loops 66 and 67 for holding the guide pins 47 and 48 instead of the solid block construction of the guide pin carrier 51 of Figures 1 to 6 inclusive. The sheet metal carrier 65 is provided with aligned holes 68 and 69 through the opposite sides of the loop 66, these holes being threaded to receive the threaded portion 54 of the adjusting screw 55. The remainder of the construction and the operation of the modification shown in Figure 10 is substantially the same as in the principal form of the invention.

Modification with adjustable spring pressure

The modification shown in Figures 11 to 17 inclusive consists of a container generally designated 70 and a friction-applying unit generally designated 71 which are inserted in the groove 16 in the edge of the vertical sash member 14 as in Figures 1 to 7 inclusive. In the modification of Figures 11 to 17, however, the guide pins remain stationary and the pressure of the coil spring is adjustable.

The container 70 (Figure 17) is channel-shaped and consists of a central portion 71² and opposite side portions 72 and 73 having upper and lower tabs 74 to 77 inclusive directed toward one another in spaced relationship. The guide pins 78 and 79 are inserted and secured in holes 80 and 81 respectively in the opposite side walls 72 and 73. The lower tabs 76 and 77 are preferably bent into the positions shown (Figure 17), but the upper tabs 74 and 75 are left in the dotted positions (Figure 17) until the device is assembled. The side wall 73 is provided with a screw hole 82 at its lower end and a tab 83 with a screw hole 84 at its upper end for securing the device to the sash.

The central portion 71 of the container 70 is provided with a tab 85 at its upper end, this tab carrying a slot 86 which receives an annular groove 87 in the head of a rod 88. The lower end of the rod 88 is threaded as at 89 (Figure 17) and is there provided with a rectangular nut 90, above which is a coil spring 91. The nut 90 thus acts as a movable and adjustable abutment for the coil spring 91.

- 10 The friction-applying member 71 consists of a channel member 92 with a central portion 93 having a friction portion 94 of fiber or other suitable material secured thereto as at 95. The opposite side walls 96 of the channel member 15 92 are provided with upper and lower elbow-shaped slots 97 and 98 respectively adapted to engage the fixed guide pins 78 and 79. The channel member 92 is also provided with slots 99 for the securing of a partition member 100 serving as an abutment for the upper end of the coil spring 91. The partition member 100 is provided with a notch 101 (Figure 16) extending inward from the rear edge thereof.

In assembling the modification of Figures 11 to 17 inclusive, the lower end of the channel member 17 is inserted above the tabs 76 and 77 in the container 70 (Figures 16 and 17) with the elbow slots 97 and 98 embracing the guide pins 78 and 79 and with the coil spring 91 inserted beneath the partition member 100. The upper end of the channel member 92 is then pushed into position within the container 70, whereupon the tabs 74 and 75 are bent from their dotted positions to their full-line positions (Figure 17). 20 30 35 The sash-holding device thus assembled is inserted in the groove or recess 17 in the manner described in connection with the principal form of the invention (Figures 1 to 7 inclusive).

In the operation of the modification of Figures 11 to 17 inclusive, the screw 88 is rotated by an ordinary screw driver in order to raise or lower the nut 90 and thus increase or decrease the pressure of the coil spring 91 exerted against the partition 100 within the friction-applying member 71. This accordingly regulates the force with which the friction member 94 engages the weatherstrip portion 23 or the side of the window frame groove 18, as the case may be. As the window is raised, the friction-applied portion 71 yields downwardly in its diagonal grooves 97 and 98, thus decreasing the friction resistance and enabling the window to be easily raised. When the window is lowered, however, the force applied to the window and the weight of the window itself 45 50 55 60 65 70 75 are exerted through the fixed guide pins 78 and 79 and the slots 97 and 98 upon the friction member 94 and thereby urge it against the weatherstrip or window frame groove, as the case may be. This increased force requires a greater effort to be exerted in closing the window than in opening it, as described in connection with Figures 1 to 7 inclusive.

Modification with adjustable slotted guide member

65 The modification shown in Figures 18 to 23 is similar in purpose to the foregoing forms of the invention and is similarly installed in a vertical groove 110 (Figure 20) in a window sash 111 reciprocable vertically in the groove 112 in the window frame 113. A weatherstrip 114 has a lip 115 projecting into the vertical groove 110 and is also provided with an outer flange 116 located between the groove 112 in the window frame 113 and the adjacent wall 117 of the sash.

111. The lip 115 is formed by bending a portion of the weatherstrip 114 back on itself so as to provide a double thickness engaging the side wall of the groove 110.

Secured within the sash groove 110 and backing up against the side wall 118 is the sash-holding device, generally designated 119, and consisting of the friction-applying unit generally designated 120 (Figure 21), the adjustment unit generally designated 121 (Figure 22), and the casing generally designated 122 (Figure 23).

The friction-applying unit 120 consists of a member 123 of channel-shaped cross section having a front wall 124 and side walls 125 bent at right angles thereto. Struck out from the slot 126 in the front wall 124 is an inwardly projecting tab 127 which serves as an abutment for a coil spring 128 by which the friction-applying unit 120 is urged into frictional engagement with the weatherstrip portion 115 (Figure 20). This frictional engagement is applied against a friction member 129 of any suitable friction-applying material such as fiber or the like, this being secured as at 130 to the front wall 124.

In order that the longitudinal urge of the coil spring 128 may be converted into a transverse motion of the member 123, the latter is provided with a pin 131 extending through holes 132 in the opposite side walls 125 (Figure 24) and having its end projecting slightly beyond the side walls 125. The pin 131 passes through and is slidable in inclined grooves 133 formed in the opposite side walls of a frame 134 forming the lower portion of the adjusting unit 121 (Figure 22). The frame 134 is formed of a pair of oppositely bent strips of material joined together as at 135 at their lower end and also coming together within the end slot 136 of the yoke portion 137 on the lower end of the adjusting screw 138, to which it is pivoted by the pivot pin 139 (Figure 22). The adjusting screw 138 is threaded into a hollow threaded sleeve 140 having an annular groove 141 adjacent its head 142, the latter being provided with a slot 143 for receiving the end of a screw driver.

The casing 122 is provided with a T-shaped spring abutment member 144 (Figure 23) having its outer ends 145 slidable in longitudinal grooves 146 and having a central stem 147 extending into the center of the coil spring 128. The casing 122 is also of channel-shaped construction having a rear wall 148 and side walls 149 perpendicular thereto. The side walls 149 are drilled as at 150 and 151 to receive a screw 152 (Figure 18) which passes through a hole 153 in a block 154 having arms 155 extending inwardly into the casing 122 and closely engaging the annular groove 141 in the threaded sleeve 140. The side walls 149 are also provided with apertures 156 (Figure 23) which provide free play for the projecting outer ends of the pin 131. The lower end of the casing 122 is provided with aligned holes 157 and 158 for the passage of a screw 159 (Figure 19) and the lower ends 160 of the side walls 149 are bent toward one another like tabs so as to provide a bottom wall for the casing 122 (Figure 23).

In the operation of the modification of Figures 18 to 23, the sash-holding device 119 is inserted in the sash groove 110 and secured firmly therein by the screws 152 and 159 passing into the sash 111. The force of the coil spring 128 against the tab 127 urges the friction-applying unit 120 downward, since the T-shaped abutment 144 is incapable of moving upward beyond the upper ends

of the slots 146. The downward motion of the friction-applying unit 120 is converted into transverse motion by the inclined slots 133 in the adjusting unit 121, so that as a result of this arrangement, the friction member 129 is forced against the inwardly projecting lip 117 of the weather strip 114. By applying a screw driver to the slot 143 and rotating the threaded sleeve 140, the frame 134 may be moved up or down, varying the adjustment of the friction-applying unit 120 relatively to the weather strip portion 117.

In this manner the sash-holding devices 119 applies a frictional force against the weatherstrip lip portion 117 in such a manner that the force is reduced when the window is raised, but is increased when the window is lowered. By this means, the person opening the window is not required to exert as much force as in closing it, and the window will be held firmly open by the friction exerted by the device. Thus this modification, like the other forms of the invention, eliminates the need for sash weights and causes the window sash to be held firmly in any desired position.

While a specific embodiment of the invention has been described and illustrated, it will be understood that various modifications may be made within the scope of the appended claims without departing from the spirit of the invention.

What I claim is:

1. A sash-holding device comprising a base member removably secured to a window sash, a friction-applying member movably mounted on said base member, means for yieldably urging said friction-applying member outwardly with respect to said base member, and independent means swiveled in the upper end of said base member for adjustably limiting the motion of said friction applying member said independent means being removably mounted and suspended between a pair of spaced lugs carried by the base member to permit the easy removal and quick assembly of the base and friction applying member.

2. A sash-holding device comprising a base member removably secured to a window sash, a friction-applying member movably mounted on said base member, a friction member secured to said friction-applying member and engageable with a portion of the window frame, means for yieldingly urging said friction-applying member transversely relatively to said base member, and independent means swiveled in the upper end of said base member for adjustably limiting the motion of said friction-applying member said independent means being removably mounted and suspended between a pair of spaced lugs carried by the base member to permit the easy removal and quick assembly of the base and friction applying member.

3. A sash-holding device comprising a base member removably secured to a window sash, a friction-applying member movably mounted on said base member, a friction member secured to said friction-applying member and engageable with a portion of the window frame, means for yieldingly urging said friction-applying member transversely relatively to said base member, independent means swiveled in the upper end of said base member for adjustably limiting the motion of said friction-applying member, said independent means being removably mounted and suspended between a pair of spaced lugs carried by the base member to permit the easy removal

and quick assembly of the base and friction applying member and means for guiding the motion of said friction-applying member.

4. A sash-holding device comprising a base member removably secured to a window sash, a friction-applying member movably mounted on said base member, a friction member secured to said friction-applying member and engageable with a portion of the window frame, means for yieldingly urging said friction-applying member transversely relatively to said base member, means independent of the first mentioned means for adjustably limiting the motion of said friction-applying member, said last mentioned means being swiveled and removably mounted between a pair of spaced lugs carried by the upper end of said base member to facilitate removal and assembly of the friction applying member, and means for guiding the motion of said friction-applying member in an oblique direction relatively to said base member.

5. A sash-holding device comprising a base member removably secured to a window sash, a friction-applying member movably mounted on said base member, a friction member secured to said friction-applying member and engageable with a portion of the window frame, means for yieldingly urging said friction-applying member transversely relatively to said base member, and means independent of the first mentioned means for adjustably limiting the motion of said friction-applying member, said last mentioned means being swiveled and removably mounted between a pair of spaced lugs carried by the upper end of said base member to facilitate removal and assembly of the friction applying member, said friction-applying member having guide portions disposed obliquely to said base member.

6. A sash-holding device for windows comprising a base member removably attached to a window sash, a channel member movable relatively to said base member and having obliquely disposed guide portions thereon, a friction member on said channel member for frictionally engaging a friction surface within the groove of the window frame, projections engageable with said guide portions, a support for said projections, and means independent of said guide portions removably suspended from the upper portion of the casing and swiveled thereto between a pair of lugs on the base member for adjustably moving said support relatively to said base.

7. A sash-holding device for windows comprising a base member, a channel member movable relatively to said base member and having obliquely disposed guide portions thereon, a friction member on said channel member for frictionally engaging an element in the groove of the window frame, projections engageable with said guide portions, a support for said projections, and an adjusting screw suspended from a swivel support at the upper end said base and threadedly engaging said support for adjustably moving said support relatively to said base.

8. A sash-holding device for windows comprising a base member, a channel member movable relatively to said base member and having obliquely disposed guideways therein, a friction member on said channel member for frictionally engaging a weather-strip element in the groove of the window frame, guide pins engaging said guideways, a movable support for said guide pins, and means for adjustably moving said support relatively to said base, said means being

removably suspended and swiveled between a pair of spaced ears on the upper end of the base to permit easy assembly of the channel member within the frame.

5 9. A sash-holding device for windows comprising a base member, a channel member movable relatively to said base member and having obliquely disposed guideways therein, a friction member on said channel member for frictionally engaging a portion of a groove in the frame of the window, guide pins engaging said guideways, a movable support for said guide pins, means removably suspended and swiveled between a pair of lugs at the upper end of the base for adjustably moving said support relatively to said base, and means for yieldingly urging said channel member away from said base.

10 10. A sash-holding device for windows comprising a base member, a channel member movable relatively to said base member and having obliquely disposed slots in the opposite side walls thereof, a friction member on said channel member for frictionally engaging within a groove in the frame of the window, guide pins engaging said slots, a movable support for said guide pins, and means removably suspended and swiveled between a pair of lugs at the upper end of the base for adjustably moving said support relatively to said base.

15 11. A sash-holding device for windows comprising a base member, a channel member movable relatively to said base member and having obliquely disposed guideways therein, a friction member on said channel member for frictionally engaging a portion of a groove in the frame of the window, guide pins engaging said guideways, a movable support for said guide pins, means for yieldingly urging said channel member away from said base, and an adjusting screw suspended from a swivel support at the upper end of said base and threadedly engaging said support for moving said support relatively to said base.

20 12. A sash-holding device for windows comprising a base member, a channel member movable relatively to said base member and having obliquely disposed guideways therein, a friction member on said channel member for frictionally engaging a portion in the guide groove of the window frame, guide pins engaging said guideways, a movable support for said guide pins, and means removably suspended and swiveled between a pair of ears at the upper end of the base for adjustably moving said support relatively to said base, said support comprising a bar having said guide pins mounted near the opposite ends thereof.

25 13. A sash-holding device for windows comprising a base member, a channel member movable relatively to said base member and having obliquely disposed guideways therein, a friction member on said channel member for frictionally engaging a portion within the guide groove of the window frame, guide pins engaging said guideways, a movable support for said guide pins, and means removably suspended and swiveled between a pair of spaced lugs on the upper end of the base for adjustably moving said support relatively to said base, said support comprising a member having loops near its opposite ends for receiving said guide pins.
